UNITED STATES PATENT OFFICE

149,326

DESIGN FOR A TRAY

Grant Wortman, Chicago, Ill.

Application April 16, 1946, Serial No. 128,647

Term of patent 3½ years

(Cl. D44—10)

To all whom it may concern:

Be it known that I, Grant Wortman, a citizen of the United States, residing at Chicago, in the county of Cook and State of Illinois, have invented a new, original, and ornamental Design for Trays, of which the following is a specification, reference being had to the accompanying drawing, forming part thereof.

Fig. 1 is a top plan view of a tray, showing my new design; and

Fig. 2 is an elevational view, partly in section.

The essential feature of the design resides in the combination on the tray disclosed of the figure, bar and border decoration, all as shown.

I claim:

The ornamental design for a tray, as shown and described.

GRANT WORTMAN.
